UNITED STATES PATENT OFFICE.

MARTIN JELALIAN, OF CRANSTON, RHODE ISLAND.

HYDROTRIPLANE FOR ARMY PURPOSES.

1,263,676.

Specification of Letters Patent. Patented Apr. 23, 1918.

Application filed December 3, 1917. Serial No. 205,044.

To all whom it may concern:

Be it known that I, MARTIN JELALIAN, a citizen of the United States, residing at the city of Cranston, in the county of Providence and State of Rhode Island, have invented certain new and useful Improvements in Hydrotriplanes for Army Purposes, of which the following is a specification.

10 The object of the invention is to provide an aerial apparatus of that character which cannot be destroyed by fire, and which may be conveniently utilized in military operations.

15 The craft is arranged with a series of propellers and wings which will afford the same considerable amount of lifting capacity and unusual amount of speed.

20 The apparatus being provided with cylindrical water tanks and having water pipe connections designed to be utilized in extinguishing fire when the certain parts of the apparatus are occasionally met by the same.

25 The object of the invention is to generally improve this class of invention and it consists in certain and special features of the construction and combination of parts as hereinafter described and claimed.

30 In describing the invention in detail, reference is had to the accompanying three sheets of drawings forming a part of this specification in which:

Figure 1 is a front perspective elevational view of the improved device.

35 Fig. 2 is a transverse sectional view of one of the alike constructed cars, illustrating the detail view of the winged device.

Fig. 3 is a front elevational view of the apparatus showing the same being equipped 40 with two main planes.

Fig. 4 is a side detail view of one of the alike constructed cars, its outer layer as partly removed and showing its interior construction.

45 Fig. 5 is a top plan view of the apparatus, its outer layer of the top plane as partly removed and illustrating its inner construction.

Fig. 6 is a top perspective detail view of 50 the forward rudder mechanism.

Referring to the drawing numeral —1, 1— designates cars which have similar construction; each of said cars are provided with windows, —3, 3— upon both sides thereof 55 for observation purposes. Each car —1, 1—

consists of three frames as frame 9, 9' and 9² rigidly connected one another by a series of vertically arranged supports —8, 8—; a wire netting 9³ is secured to said cars and a layer of sand or emery cloth —9⁴— secured to the 60 same.

Secured upon the bottoms of said cars is a spring cushion device which consists of longitudinally extending flat supports —2, 2— which are bolted to the lower frames —9²— 65 as at points —6', 6— and said supports having integral supports —4, 4— extending from the bottoms thereof to converging positions and having integral collars —5, 5— at the free ends thereof and also shafts 70 —6, 6— extending therfrom; tubular members —6², 6²— are slidably mounted upon the end portions of said shafts —6, 6—; expanding coil springs —7, 7— have one of their ends secured to the integral collars 75 —5, 5— and the other ends attached to the free end portions of the tubular members —6², 6².

The shafts —6, 6— are slidable within the tubular members —6², 6²—; said members 80 —6², 6²— are provided with integral hooks —8³, 8³— to receive strap connections —6³, 6³— in order to keep the latter in their normal position; supporting wheels —5², 5²— are loosely secured within the lower portions of said members and mounted upon the shafts —5³, 5³—.

Projecting outwardly from the rear of the middle frames of each car —1, 1— are flat outwardly extending tail portions —10, 10— 90 and pivoted at the rear ends as at points —12', 12'— are usual form flat vertical rudders —12, 12—.

Located forwardly at the bottom of each car —1, 1— is a motor which has a shaft 20; 95 mounted upon said shaft —20— is a sprocket wheel —19— which has a chain connection —16— with a sprocket wheel —18— mounted upon the wing shaft —17— which is provided with a crank at each end thereof and 100 mounted upon the middle frame —9'—.

Also mounted upon said wing-shaft —17— is a sprocket wheel —16'— which has a chain connection —15'— with a sprocket wheel —14'— mounted upon the shaft 105 —14— which is located upon the upper frame —9— of each car —1, 1—.

Mounted upon said shaft —14— is a sprocket-wheel —27'— which meshes with sprocket-wheel —26— mounted at the rear 110

end of the shaft —25'—. Secured at the forward end of said shaft —25'— is a revolving propeller —25—.

Located at the rear upon the bottom of each car —1, 1— is a motor —22— which has a chain connection —22'— with a sprocket-wheel —27— to drive the shaft —26'— which is provided with a revolving propeller —26'— at each end thereof.

10 Extending outwardly from each side of each car —1, 1— is a pair of laterally projecting bird-like wings —30, 30— which are pivotally connected as at points —31, 31— forwardly of the upper frame —9—.

15 Each wing —30, 30— is provided with a vertically arranged supporting arm —60— having an eyelet —60'— at its lower end and loosely mounted upon the end portion of the crank wing-shaft —17— and its upper 75 end pivotally connected as at 59'— upon the bottom of a rectangular shaped flat support —63—.

20 The rectangular shaped supports —63— are provided with equi spaced perforations 25 to loosely receive wing supports —59', 59'— which are pivotally united to the wings —30—.

25 Each wing —30— consists of longitudinally extending supports —30', 30'— provided with equi-spaced perforations to receive transversely arranged supports 30', 30'—; a fine wire netting —30'— is secured to said supports and a layer of sand or emery cloth carried upon the top and bottom of the netting. However, if desired a fine lather or transparent flexible celluloid 35 may be used for the same.

30 The wing shaft —17— is also provided with integral collars —60', 60'— and removable threaded collars —60', 60'— secured at each end thereof in order to keep the support arms —60', 60'— to their normal position.

35 Arranged upon the top of each wing —30, 30— is a pair of yieldable elastic straps —39', 39'— which have one of their ends secured to a pair of integral hooks provided upon the top of the wing —30— and the other ends attached to the support 50 —61— extending transversely above the car —1— and a pull spring —34'— arranged centrally which has one of its ends connected to the integral hook —34'— and the other end attached to the end portion of the transversely arranged horizontal support —60— which is rigidly connected to the vertical supports —59, 59— said supports also have connection with supports —59'— as at points —59'—, in the manner shown in 55 Fig. 2.

60 Said elastic straps and pull-spring connections are designed to support said wings and also to facilitate the upward movements of the same.

65 Forward connecting gang-way —54—

comprising two pairs of tubular rods —49, 49'— which form the top and bottom of the same extends from the top frame —9— and the middle frame —9'— of the car —1— to the top and middle frame of the adjacent car and is connected thereto. The tubular rods —49, 49— have a series of vertically arranged connecting supports —54— and also transversely extending supports —54'— a wire netting is secured to said supports and a layer of emery cloth —51'— is secured to the netting.

70 Arranged centrally and extending forwardly of said connecting gang-way —54— is a flat vertical rudder —48— having its rear end connected to the lower portion of a tubular curved shaft —51'—; said shaft —51'— is loosely mounted upon a vertical stationary shaft —52'— which is provided at the forward end of a support —51— 75 which is connected to a pair of tubular rods —49, 49— which form the bottoms of the gang-way.

75 The curved tubular shaft —51'— has a hand-wheel —51'— secured at its upper end 80 and also a portion of an integral sprocket-wheel —52'— adapted to receive the free end portion of a rudder lock —54'— which is mounted upon a transverse fixed rod —52'— located upon a platform —54'— and 85 having a coil spring —54'— upon each side thereof.

80 A connection gang-way is arranged at the rear of the car —1, 1— which consists of two pairs of tubular rods —53'— 53'— which 90 form top and bottom of the same, connected to the cars —1, 1— in the same manner as the forward gang-way, as described, and having transversely arranged connecting wires —53'— arranged there between.

95 Arranged forwardly of each car —1, 1— is a fixed gun platform —27— and mounted upon said platform is a gun —32—.

100 Fixed at the rear of each of said cars is a fixed gun platform —27'— which carries a gun —32'—.

105 Located between the cars —1, 1— is a plane —29— which is connected to the middle frame —9'— of the cars —1, 1— and having a gang-way —52— arranged centrally upon the top of the same and a slideable door formed into the cars —1, 1— in order to pass from one to the other.

110 Projecting outwardly from the outer side of the middle frame —9'— of each car —1, 1— are planes —32', 32'— which carry buoyant cylinders —45, 45— connected upon the bottoms thereof by means of straps —43—46—, and mounted above said planes —32', 32'— upon a series of vertical supports 115 —15', 15'— is a plane —32'—. Secured upon the bottom of said plane —32'— above each car —1, 1— are cylindrical water tanks —39'— and 39'— which are provided with straps for securing to the plane —32'—; water pipe 120

connections extend from said cylinders to the forward and the rear part of each car —1, 1— and designed to extinguish fire when the certain parts of the apparatus are 5 met by the same.

A sliding door —46— is arranged into said plane —32³— above each car —1, 1— and ladders —46— extending from said cars to the latter.

10 Located centrally upon said plane —32³— is a motor —31³— which has a shaft —31²— extending forwardly therefrom and having a revolving propeller —31'— secured at the end thereof.

15 Mounted above the plane —32³— is a plane —32⁵— which is secured upon a series of vertical supports —15²—. Said plane —32⁵— consists of a pair of longitudinally extending supports —32⁷— and also transversely arranged connecting supports —32⁶—; a wire netting —32⁹— is secured to said supports and a layer of emery cloth or transparent flexible celluloid secured upon the top and bottom of the netting.

20 25 Planes —32', 32²—, 32³ and —29— are also provided with wire netting and emery cloth in the same manner as the top plane —32⁵—. However, if desired, layers of fine tin may be employed at the outer ends of 30 said planes.

Extending above the top plane —32⁵— is a transverse support —49'— which is secured upon the top of a series of vertical supports, and said support having connecting wires —49², 49³— extending to the plane —32⁵—.

35 In Fig. 3 the apparatus is shown as equipped with a single car having planes —34, 34— projecting from each side thereof, 40 a main plane —34'— is arranged above said car —1— and having vertical connecting supports —8'— and also vertical supports —8²— which project through the plane —34'— and support a small plane —36—, 45 connecting wires —39— extend from the supports —37— to the plane 34'.

The operation of the device will be readily understood and it will make obvious that by the arrangement of parts as described 50 the apparatus has unusual amount of lifting capacity and also considerable amount of speed when all of the propellers and wings are in action.

The arrangement of water tanks and 55 water pipe connections and employment of emery cloth, as described, will prevent the fire from affecting the apparatus and thus adapt the craft to be most convenient for use in military operations.

60 Thus describing my invention, what I claim and desire to secure by Letters Patent is:

1. An apparatus of the character described, a hydrotriplane comprised of two 65 main body sections or cars located side by

side and extending longitudinally to each other, each of said body sections consisting of three metallic frames having a series of vertically arranged connecting supports surrounding the same, a wire netting secured to said supports of each of said cars and a layer of emery cloth secured to the latter, a small plane arranged between said cars and the ends of the same being secured to the middle frames of the same, and said small plane made of a series of connecting supports, a wire netting and a layer of emery cloth secured to the same, planes projecting outwardly from the middle frames of said cars and having buoyant cylinders 70 secured upon the bottoms thereof.

2. An apparatus of the character described, a hydrotriplane comprised of two main body sections or cars having connecting means at the forward and the rear parts 75 thereof, a plane mounted above said cars and located upon a series of vertically arranged supports, a second plane mounted above said first mentioned plane and carried by a series of vertical supports connected to said first mentioned plane, and each of said planes consisting of a series of transversely arranged supports, wire nettings secured to the latter and layers of emery cloth carried upon each side of the 80 nettings, a motor located centrally upon said first mentioned plane and having a shaft 85 extending forwardly behind the plane and having a revolving propeller secured at the end thereof, a smaller plane carried between 90 said cars and having a gang-way arranged 95 centrally upon the top of the same.

3. An apparatus of the character described, a hydrotriplane comprised of two main body sections each consisting of three 100 frames forming lower, upper and middle frames, a flat outwardly extending tail portion projecting from the rear of each side of the middle frame of each of said cars and flat vertical rudders pivotally connected at the rear ends of the latter, longitudinally extending flat supports secured upon the bottoms of the lower frames of said cars 105 and said supports having integral supports extending downwardly to a converging position and each set having an integral collar and also a shaft extending therefrom, tubular members slidably mounted upon the free end portions of said shafts, expanding coil-springs having one of their ends secured 110 against said integral collars and the other ends attached to the end portion of said tubular members, strap hooks carried by the latter and having strap connections extending 115 from said hooks to the lower frames of 120 said cars.

4. An apparatus of the character described, a hydrotriplane consisting of two main body sections or cars having planes projecting outwardly from each side there- 125 130

of, winged means arranged forwardly to said planes and pivotally connected to said ears, each of said wings comprising longitudinally extending supports adapted to conform to the exact curvature of the wing and provided with equi-spaced perforations to receive a series of transversely arranged supports; a wire netting is secured to the latter and a layer of emery cloth carried upon the top and bottom of the netting, a pair of elastic straps and a pull spring connection arranged upon each of said wings and said pull-springs and elastic strap connections designed to support said wings and also to facilitate the upward movements of the same.

5. An apparatus of the character described, a hydrotriplane comprising two main body sections or cars having two superposed main planes mounted above the same upon a series of vertical supports, planes projecting outwardly from said cars and connected by supports to said main planes, and a smaller plane arranged between the cars and connected thereto, cylindrical water tanks carried upon the bottom of the lower of said first mentioned main planes and having water pipe connections extending into said cars, slideable doors arranged into the lower of said main planes and ladders extending from said cars to the latter, a motor located centrally upon the top of the lower of said main plane.

6. An apparatus of the character described, a hydrotriplane comprising two main body sections or cars having connecting gang-ways arranged between the same at the rear and forward part thereof, each of said cars comprised of three frames forming lower, upper and middle frames connected one to another by a series of vertical supports, a pair of bird-like wings forwardly of each of said cars and pivotally connected to the upper frame of the same, crank wing shafts extending transversely to said cars beneath said wings and located upon the middle frames of the same, a vertically arranged supporting arm for each

of said wings having its lower end provided with an eyelet loosely mounted upon the end portions of said wing-shafts and the upper end of said vertical supporting arm pivotally connected to a flat rectangular support, said rectangular support having a series of wing supports pivotally united to said wings.

7. An apparatus of the character described, a hydrotriplane comprised of two main body sections or cars having connecting gang-ways arranged between the same at the rear and the forward parts thereof, said forward gang-way comprised of two pairs of transversely extending tubular rods forming the top and bottom of said gang-way extending between said cars and connected to the upper and middle frames of the same, and each pair of said tubular rods having a series of transversely extending connecting supports and also vertically arranged supports, a wire netting is secured to said transversely extending connecting supports and a layer of emery cloth secured to the netting, a flat vertical rudder projecting forwardly from said gang-way.

8. An apparatus of the character described, a hydrotriplane having two main body sections or cars and planes mounted above the cars by means of a series of vertical supports and also a plane projecting outwardly from each side of the cars, a vertically reciprocating wing upon each side of each of said cars and arranged in front of said planes, revolving propellers at the forward ends of said cars, a fixed gun platform arranged near the forward end of each of said cars and having guns mounted upon the same, gun platforms arranged near the rear end of said cars and having guns mounted upon the same.

In testimony whereof I affix my signature in the presence of two witnesses.

MARTIN JELALIAN.
